(57) **CLAIM**

The ornamental design for an inflatable basketball stand, as shown and described.

DESCRIPTION

FIG. 1 is a perspective view of an inflatable basketball stand showing my new design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is a perspective view showing the design in association with environmental structure in broken lines; the broken lines being for illustrative purposes only; and forming no part of the claimed design.
